UNITED STATES PATENT OFFICE.

JOHN F. HARTNEY AND GEORGE R. LARKIN, OF DAYTON, OHIO, ASSIGNEES TO THE FLASH FIRE EXTINGUISHER COMPANY, OF DAYTON, OHIO, A CORPORATION OF OHIO.

FIRE EXTINGUISHER.

Application filed August 21, 1925. Serial No. 51,592.

This invention relates to fire extinguishers, and the primary object of the invention is the provision of a fire extinguisher which will be handy to operate, and positive and effective 5 in its operation.

An additional object is the provision of a finger operated push button on the side of the container which will be readily depressed by the finger of the operator to control the flow 10 of fluid from the container, it being intended that the fire extinguisher shall be of the portable type to be held in the hand of the operator in such a manner that the push button is accessible to a finger of the hand which 15 holds it.

A further object is the provision of a closed valve chamber which is connected to opposite ends of the container by means of flexible pick-up tubes, the control of the fluid through 20 these tubes being governed by a valve closure which closes the tube leading to the high side of the container. This valve closure is governed by a weighted control lever which is pivoted to the valve chamber and at one end 25 is pivoted the valve closure so that a limited movement of the valve closure about its pivot is permitted..

A still further object of the invention is the provision of an end head for the container 30 to close one end thereof, this end head being provided integrally with a chamber which holds a compressed gas capsule by means of which an expelling pressure is applied to the fire extinguishing fluid within the container. 35 This end head is provided with a central orifice through which the supply of fire extinguishing fluid may be replenished, this orifice being closed by a nut which threads within the end head, and which provides a mounting for a 40 plunger which is adapted to permit the release of the compressed gas from the capsule.

With the above objects in view, and with further objects and advantages as will be pointed out more particularly in the following description and claims, reference is made 45 to the accompanying drawings, in which—

Fig. 1 is a central longitudinal section of the fire extinguisher,

Fig. 2 is a section on the line 2—2 of Fig. 50 1 and

Fig. 3 is an end view of the pendulum control valve.

In the drawings is shown a fire extinguishing fluid container 1 of generally cylindrical shape. At one end the container is closed by

an end wall 2' constructed integral with the main body of the container and at the opposite end the container is closed by an end head 2 of substantially the same diameter as that of the container 1, and which is connected thereto by bracing along the rim 3. The end head 2 is constructed integrally therewith with a cylindrical central hollow chamber 4 which is adapted to loosely contain or hold a gas generating capsule 5 of ordinary commercial type. In the end of the chamber 4 is a series of openings 6 through which the pressure may be communicated to the interior of the container 1, when it is released from the capsule 5. The end of the chamber 4 is closed 60 by means of a screw plug or nut 7 which is threaded within the end of the chamber 4 as shown at 8, a suitable packing washer 9 being provided to make the joint pressure-tight. Within the end of the nut 7 is threaded a 70 spring retainer and capsule positioner 10 which is provided with a hollow cylindrical portion 11 adapted to fit neatly over the end of the capsule so as to prevent the capsule from moving endwise. The spring retainer 75 10 holds a spring 12, the other end of which presses against a washer-like sleeve 13, which is loosely mounted on a plunger 14 and abuts against an enlarged portion 15 on this plunger. The plunger 14 acts as a firing pin and is 80 provided with a pointed end 16 which punctures a sheet metal disc in the end of the capsule 5 when the plunger is depressed by means of the knob 17 which is threaded or otherwise fixed to the end of the enlarged portion 15 of 85 the plunger. Suitable packing is provided at 18 between the sleeve 13 and the screw plug or nut 7. It will thus be seen that the knob 17 may be bumped against an object so as to 90 depress the plunger 14 against the action of the spring to release the compressed gas from 95 the capsule 5, and as soon as the depressing force is removed from the knob 17 the spring 12 will return the plunger to its normal position and the sleeve 13 pressed against the 100 washer 18 will maintain the joint pressure-tight and prevent the leakage of gas or fluid.

Mounted in an intermediate position within the container 1 is a valve chamber 19 which is shown in the form of a casting 20 provided with an end plug 21, which has a threaded end 22 projecting through a hole within the container 1. The valve chamber is held in position within the container by the retaining nut 23 threaded on the end 22. An end 110

nut 24 is threaded on the end of the threaded portion 22 and retains a cork packing 25 therein. Slidingly mounted for endwise movement within the end nut 24 is a plunger 26 on the end of which is threaded or otherwise secured a finger operated push button 27. The plunger 26 has an enlarged portion 28 against which a spring 29 presses to retain the plunger in the position shown in Fig.

10 1. The other end of the spring 29 bears against a flange at the lower portion of the part 21. The end of the plunger 26 is provided with a tapered valve closure 30, which makes a tight fit with the orifice provided 15 in the upper portion of the casting 20 so as to secure the orifice against the passage of fluid from the valve chamber 19 when the plunger is in its position as shown. The container 1 is adapted to be held in the hand 20 of the user and when it is grasped in the ordinary manner the push button 27 will be in a convenient location to be readily pressed by one of the fingers of the user so that the release of the fluid from the valve chamber 25 19 is under the instant control of the user. When pressed inwardly the plunger moves the closure 30 so that the fire extinguishing fluid is forced out of the container by means of the discharge pipe 31 which is tightly fitted 30 within a depression in the part 21 and the other end of which extends slightly through the end of the container 2 where it is fixed in position.

35 The fluid within the container 1 is admitted to the valve chamber 19 by means of the two flexible pickup tubes 32 and 33 which are provided with weighted ends 34 and 35 respectively, and the opposite ends of which are fixed within the plugs 36 and 37 respectively, which are screwed within the casting 40 20. The ends of these plugs 36 and 37 are provided with valve seats adapted to be closed by a spherical ended valve 38. This valve is pivoted on a pin 39 for slightly limited 45 movement on a bifurcated end of a lever 40, which is pivoted on a screw 41 mounted in the back of the casting 20. The lever 41 is provided with a weighted end 42 on the opposite side of the pivot from the valve 38. 50 The force of gravity will thus control the closure of the ends of the plugs 36 and 37 so that the plug leading to the high side of the container will automatically be closed by the pressure exerted on the valve 38 through 55 the action of the weight 42. A means is thus provided for maintaining one of the plugs open and for automatically closing the plug leading to the high side of the container. The chamber 19 is closed with the exception 60 of the openings mentioned at the interior of the container, by means of the end plate 43 which is attached to the casting 20 by means of suitable screws 44.

The operation of the device is as follows: 65 Fire extinguishing fluid is supplied to the

interior of the container 1 by removal of the screw plug or nut 7 and the plunger and spring retainer which are held thereon. With the capsule 5 removed, the fire extinguishing fluid can be poured into the end head 2 of the 70 container. A sealed capsule containing compressed gas is then placed in position within the chamber 4 of the end nut 7. When the knob 17 is struck the pressure is released from the capsule and the fluid within the container is then under pressure. With the container grasped in one hand and pointed towards a fire, the fluid is released from the discharge opening as desired by pressing with a finger upon the push button 27. The 75 passage through the flexible pickup tube which extends through the higher side of the container is closed by means of the pendulum control valve, so that it will be assured that only liquid is supplied to the valve chamber 80 85 until the liquid is exhausted.

The flexible pickup tubes will of course seek the lowest points of the container ends at all times in the customary manner. The slight movement permitted to the valve 38 90 about its pivot assures the proper seating of the spherical end of this valve with the end of the plug with which it contacts. Regardless of how the device is held, an instant supply of fire extinguishing fluid is always available, and the control of this supply is effected immediately and in accordance with the user's wishes.

We are aware that various modifications may be made within the scope of our invention and it is not intended that we should be limited to the precise construction which has been shown for purposes of illustration.

We claim:

1. A portable fire extinguisher comprising 105 a fluid container adapted to hold a quantity of fire extinguishing fluid, an end head at one end of said container and providing a chamber for holding a compressed gas cartridge, means for releasing the compressed gas from said 110 cartridge to create an expelling pressure within said container, a discharge orifice at one end of said container, a valve chamber within said container fixed to an intermediate part of a side wall of the container, a pickup tube extending from said valve chamber to each end of said container, and a finger operated push button mounted on the side of said container adjacent said valve chamber for controlling the supply of fluid from said valve chamber 115 to said discharge orifice.

2. A portable fire extinguisher comprising a cylindrical fluid container, an end head for said container fixed thereto and provided with a chamber to hold a pressure generating capsule, an end nut threaded to said head and forming an end closure for said chamber, a firing pin held in said end nut for endwise movement, a closed valve chamber near the center of said container, said chamber having 125 130

- means extending through a side wall of the container for attaching said chamber in position, a pickup tube extending from said chamber to one end of said container, a second tube 5 extending from said chamber having its end opposite to said pickup tube, a valve closure adapted to close the tube leading to the high side of the container, a gravity control means within said chamber for operating said valve closure, a discharge tube extending from said valve chamber along one side of said container to the end thereof, a closure between said valve chamber and said discharge tube, and finger 10 operated means on the side of said container adjacent to said chamber to operate said closure to permit the release of the fluid within said container through said discharge tube.
3. In a portable fire extinguisher, a fluid container, a valve chamber therein having a threaded portion projecting through a side 15 wall thereof, means outside of said container for engaging said portion to hold the chamber in position, gravity actuated valve mechanism housed in said chamber, a flat side plate closing one side of said chamber, and means for attaching said plate in position.
4. In a portable fire extinguisher, a fluid container, a valve chamber therein having a threaded portion projecting through a side 20 wall thereof, means outside of said container for engaging said portion to hold the chamber in position, gravity actuated valve mechanism housed in said chamber, and a finger operated push rod extending through said threaded portion for controlling the flow of fluid from 25 said chamber.
5. In testimony whereof we affix our signatures.
- JOHN F. HARTNEY.
GEORGE R. LARKIN.
